UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK N. Y., A CORPORATION OF DELAWARE.

TYPEWRITING MACHINE.

Application filed December 1, 1925. Serial No. 72,431.

This invention relates to twin-platen type-writing machines, and more particularly to the marginal stop mechanism. Heretofore, such machines have been provided with a single set of marginal stops, and it has been customary to reset the stops every time that the carriage was moved to bring either of the platens to the printing field.

In this invention marginal stops are provided to limit the travel of the carriage for each platen, or for each web. Means are also provided whereby the carriage may be moved to receive typing on either one of the webs without necessitating resetting of the marginal stops.

In the Underwood machine, it has been customary to provide at the left-hand side of the machine a marginal stop which controls the right-hand margin of the work-sheet. This stop operates a carriage-alarm, and locks the keys, means being provided for releasing the keys if desired. In this invention, the same advantages are secured for both platens upon the one carriage.

To enable the carriage to be positioned to receive typing upon either web without necessitating the disturbing of the marginal stops, there is provided a special stop, which is carried by the left-hand marginal stop of the right-hand platen. When it is desired to move the carriage from right to left to present the right-hand web to the printing point, said special stop is swung away from an interfering lug on the carriage, and the carriage is freed to move along its rails, in both directions. The special stop is carried by the left-hand marginal stop, and may be set therewith in the regular manner. Said special stop is held in its normal or operating position by means of a spring; and, in order to clear the lug on the carriage, the special stop is swung to its ineffective position.

Although this invention is illustrated as applied to an Underwood fan-fold type-writing machine, it will be understood that the same may be used in connection with a variety of machines.

Other features and advantages will hereinafter appear.

In the accompanying drawings,

Figure 1 is a plan view of the invention as applied to an Underwood twin fan-fold type-writing machine, and shows the marginal stops for both webs.

Figure 2 is a cross-sectional view, in elevation, through the center of said Underwood machine, and shows the means for locking the type-keys.

Figure 3 is a perspective view, showing the left-hand marginal stops and means for permitting the repositioning of the carriage.

Figure 4 is a detail, showing the key-locking means in operated position.

Figure 5 is a detail, showing the locking position of the stop-device illustrated in Figure 3.

This invention is preferably applied to an Underwood twin fan-fold typewriting machine, such as illustrated in the Messenger Patent 1,363,197, dated December 21, 1920; but it should be understood that the same may be used in connection with many other types of machines. In said machine, there is provided a pair of platens 10 and 11, which are revolubly mounted on end plates 12 of individual platen-frames, both platen-frames being displaceably mounted on a carriage 13. The carriage is slidably mounted on rails 14 fast to a frame 15, and the letter-space travel of the carriage is controlled by means of a spring-drum 16, operatively connected to the carriage by means of a tape 17 and an escapement mechanism 18, which is operatively connected to the carriage by means of a rack 19 and a pinion 20. The platens 10 and 11 are operatively connected to individual line-spacing mechanisms, not shown, by means of gears 22 fast to platen-axes 23, engaging with pinions 21, which, in turn, mesh with gears 24 fast on the inner ends of shafts 25, the latter carrying at their outer ends finger-wheels 26.

In this invention there are provided two sets of marginal stops, one for each platen, and each set comprises one right-hand and one left-hand marginal stop. The right-hand marginal stops in the Underwood machine include blocks 27, slidably mounted on a shaft 28 fast to the frame 15 and may be locked in place by means of pawls 29 engaging with a rack 30. In order to move said marginal stops, the operator releases the pawls 29 by means of finger-pieces 31, thereby freeing the pawls from the rack and enabling the sliding of the stops.

The left-hand stop, however, has to be considerably modified in order that the carriage may be passed over it without disturbing its position. In operation, the car-

riage travels towards the left-hand stop by letter-spacing the same until a controlling member or lug 32, which forms an integral part of the carriage, engages an inclined portion 33 of a cam-plate 34 and cams the cam-plate downwardly, thereby ringing a bell by means of a bell-crank 35 and other mechanism, such as disclosed in the patent to John McLaughlin, No. 958,818, dated May 24, 1910. By further letter-spacing the carriage, the lug 32 engages with a higher portion 36 of said cam-plate, thereby swinging the bell-crank 35 forwardly, so that a pin 37 will engage with an arm 38 fast to a shaft 39, which carries fast thereto a bail-piece 40, thereby locking the type-keys 41, and preventing the operation of the type-bars 45. Sometimes the keys are locked before a complete word is typed, and, in this case, it may be necessary to temporarily release the keys. To this end, there is provided a plunger 42 mounted in the frame 15, the plunger actuating against a spring 43, and by depressing the plunger the pin 37 on the bell-crank 35 is thrown out of engagement with said arm 38, thereby permitting a spring 44 to draw on the bail-piece 40, so as to permit the depression of the keys.

By the left-hand marginal stop the carriage is completely locked after typing a predetermined number of letter-spaces after the bell rings, and there is no way of moving the carriage further unless the stop is reset. In this invention, there is provided a special stop 46 made out of a separate piece, which is rockably mounted on the shaft 28. Said stop 46 is held in its normal position, as shown in Figure 3, by means of a spring 47 coiled around the shaft 28. When it is desired to move the carriage past a tooth 48 at the end of the special stop, the stop is swung upwardly by means of a finger-piece 49, thereby clearing the lug 32 on the carriage. In order that the special stop may be held in place, there is provided a plate 50 fast to a block 51 by means of screws 52. Said plate extending downwardly at 53 and hooking over said stop 46 holds the same in place.

The cam-plate 34 forms an integral part of the block 51, which is slidably mounted upon the shaft 28, and may be locked in any of a plurality of positions. To this end, there is provided a pawl 54 pivotally mounted on a pin 55 fast to the block 51, the pawl being releasable by means of a finger-piece 56 forming an integral part thereof. The pawl 54 has a plurality of teeth designed to engage with teeth on a rack 61, which is pivotally mounted on the shaft 28, and is held in its normal position by means of springs 62. In order to facilitate the operation of the pawl 54, there is provided a second finger-piece 57, which is secured to the block 51 by means of screws 58 and fa-

cilitates the sliding of the block to any desired position. The piece 57 is secured to the block 51 by means of the screws 58, and is provided with an index or finger 59, which co-operates with a graduated scale 60 to position the marginal stops.

The right-hand stop-devices co-operate with a lever 63, pivotally mounted at 64, the lever being provided with a tab 65, engaging with a lug 66 on the blocks 27. Said lever 63 is provided with an upwardly-extending finger-piece 67, near the carriage-return finger-piece 68, so that said lever may be swung downwardly, thereby permitting the free movement of the carriage from left to right.

Variations may be resorted to within the scope of the invention, and portions of the improvements may be used without others.

Having thus described my invention, I claim:

1. The combination with a typewriting machine having a twin platen and a carriage therefor, of sets of marginal stops for controlling the travel of the carriage within the range of each platen, and means whereby the carriage may be moved to receive typing upon either platen without disturbing the position of said marginal stops.

2. The combination with a typewriting machine having a twin platen and a carriage therefor, of sets of marginal stops for controlling the travel of the carriage within the range of each platen, each set of marginal stops having right and left hand stops co-operating with a lug on the carriage, the left-hand stop controlling the right-hand margin of the left-hand platen being provided with means to permit the passing of the carriage from one side to the other of the stop while the same remains in its gagging position.

3. The combination with a typewriting machine having a twin platen and a carriage therefor, of sets of marginal stops for controlling the travel of the carriage within the range of each platen, and means whereby the carriage may be moved to receive typing upon either platen without disturbing the position of said marginal stops, said means including a releasable member mounted on one of the marginal stops.

4. The combination in a typewriting machine of a twin platen, a carriage therefor, adjustable stop-devices for limiting the travel of said carriage within the range of the platens, said stop-devices having a pair of right and left hand marginal stops for each platen, and means for operatively connecting the left-hand marginal stops of both platens to a carriage-alarm a predetermined number of letter-spaces before the end of the line.

5. The combination in a typewriting machine of a twin platen, a carriage therefor,

- adjustable stop-devices for limiting the travel of said carriage within the range of the platens, said stop-devices having a pair of right and left hand marginal stops for each platen, means for operatively connecting the left-hand marginal stops of both platens to a carriage-alarm a predetermined number of letter-spaces before the end of the line, and means for locking the typewriter-keys a predetermined number of letter-spaces after operation of the carriage-alarm. 5
6. The combination in a typewriting machine of a twin platen, a carriage therefor, 15 adjustable stop-devices for limiting the travel of said carriage within the range of the platens, said stop-devices having a pair of right and left hand marginal stops for each platen, means for operatively connecting the left-hand marginal stops of both platens to a carriage-alarm a predetermined number of letter-spaces before the end of the line, means for locking the typewriter-keys a predetermined number of letter-spaces 20 after operation of the carriage-alarm, and means for releasing said locking means, to permit the carriage to travel a predetermined number of letter-spaces. 25
7. The combination in a typewriting machine of a twin platen, a carriage therefor, adjustable stop-devices for limiting the travel of said carriage within the range of the platens, said stop-devices having a pair of right and left hand marginal stops for each platen, means for operatively connecting the left-hand marginal stops of both platens to a carriage-alarm a predetermined number of letter-spaces before the end of the line, means for locking the typewriter-keys a predetermined number of letter-spaces 30 after operation of the carriage-alarm, means for releasing said locking means, to permit the carriage to travel a predetermined number of letter-spaces, and means to permit the 35 movement of the carriage to bring either of the two platens to the printing field. 45
8. The combination in a typewriting machine of a twin platen, a carriage therefor, adjustable stop-devices for limiting the travel of said carriage within the range of the platens, said stop-devices having a pair of right and left hand marginal stops for each platen, and means on the left-hand marginal stop of the left-hand platen to permit the free movement of the carriage to 50 bring either platen to the printing field. 55
9. The combination in a typewriting machine of a platen, a carriage therefor, and means for controlling the travel of said carriage within predetermined portions of said 55 platen, said means having pairs of adjustably mounted marginal stops effective to check the travel of the carriage in either letter-space or return direction. 60
10. The combination in a typewriting machine of a platen, a carriage therefor, means for controlling the travel of said carriage within predetermined portions of said platen, said means having pairs of adjustably mounted marginal stops effective to check 70 the travel of the carriage in either letter-space or return direction, and manually operable means to permit the shifting of the carriage over the marginal stops without changing the position thereof. 75
11. The combination in a typewriting machine of a twin platen, a carriage therefor, means for controlling the travel of the carriage within the range of the platens, said means having right and left hand marginal 80 stops and a lug on said carriage co-operating with said stops to check the movement of the carriage in either letter-space or return direction, and means for freeing the carriage from the marginal stops to permit the shifting of the carriage to present either platen to the printing field. 85
